UNITED STATES PATENT OFFICE.

FRANZ KRUCKENBERG, OF HEIDELBERG, GERMANY.

METHOD OF, AND DEVICE FOR, DAMPENING NOISES, CAUSED BY PROPELLERS AND OTHER QUICKLY MOVING BODIES.

Application filed March 9, 1928, Serial No. 260,397, and in Germany March 12, 1927.

This invention relates firstly to a method of damping the noises caused by quickly moving and rotating machine-parts or other objects, for instance quickly rotating propellers, 5 high-speed tram-cars, high-speed railway-cars and the like, and secondly to a device for practicing that method. Another object of the invention is to keep the respective noises off buildings and the like located in the neighbourhood of the bodies producing the noises. 10 The ends in view are attained by the provision of sound-damping or reflecting walls arranged in a suitable manner relatively to the respective buildings or other places.

15 Suitable arrangements and combinations of the parts concerned are illustrated diagrammatically and by way of example on the accompanying drawing, on which Figure 1 is a side-view of the rear portion of a high-speed vehicle, driven by a propeller located at that end; Figure 2 is a similar view showing, however, the front end of such a vehicle with the propeller located at this end; Figure 3 is a perspective representation of the rear end 20 of a high-speed railway vehicle also driven by a propeller, located at that end, and Figure 4 shows a modification, in which the propeller of the high-speed railway vehicle is arranged at the front end of the same.

25 On the drawing (Fig. 1) 5 denotes a suspended railway-car, more precisely the rear end of a high speed suspended railway-car, and 7 is an annular wall encompassing the propeller 6. This wall consists of a material especially suited for damping purposes, and its thickness in axial direction is preferably that, indicated in Fig. 1 in dotted lines, that is to say, it is reduced in thickness in the direction of the front edge and to the rear edge 30 of the annulus, and the thickest part lies nearer to the front edge than to the rear edge, whereby the resistance, which the annulus offers to the air becomes the smallest possible and the streaming away of the air proceeds in the most favourable way. First of all, the sound waves are prevented from propagating radially with respect to the propeller. The dotted line 8 shown only on the top of the annulus 7 indicates the boundary of the air current produced by the propeller, if no annu-

lus like 7 or equivalent member is provided, and the lines 9, which of course, must be assumed to extend forth from the propeller on its entire circumference indicate the sound waves, which the propeller produces. The 55 intensity of these waves increases from the hub of the propeller to the ends of its blades. The lines 10 and 11 include that space, which the sound waves cannot enter because of the provision of the damping annulus 7. The 60 direction of these latter two lines, or the shape of the space they enclose, will vary with the speed of the vehicle. If that speed becomes greater and greater the line 10 will finally extend vertically and the line 11 horizontally. 65

The wall of the damping ring 7 is preferably designed as an elastic-solid skin in order to render it as indifferent as possible in acoustic respect. A particularly suitable material, 70 which not only is very elastic, but also is of low weight, and non-resonant, is scum-rubber, which is a rubber mass enclosing very many gas-bubbles.

In Fig. 2 the shape of the damping ring 75 f is somewhat different from that shown in Fig. 1, in that its radius becomes gradually shorter in forward direction. I wish it to be understood, however, that this is merely an example. As to the thickness of the wall 80 of the ring, the proportions are practically the same as in Fig. 1.

In Figs. 3 and 4 the assumption is made, that a suspended high-speed railway-car is just stopping at a station. 12 indicates the 85 platform of the latter. The annular damping member 7 is carried at its top by a longitudinal member 13, extending along the top of the vehicle (for particulars as regards to this member see the U. S. Patent 1,628,595) 90 and at its sides by fin-like parts 14. As viewed in plan, the ring 7 and the outer end portions of the ribs 14 project slightly over the edge of the platform 12. The fins 14 not only assist in supporting the ring, but they 95 serve also as deflectors for moving backward any persons who may be standing at the edge of the loading platform. This is important during the starting of the vehicle, especially if there is a crowd on the platform. The 100

damping ring in such cases protects persons from being hurt by the blades of the propeller.

Be it understood, that the damping wall, which can be shaped annular or in any other suitable way, need not be connected with the vehicle or other object, producing the sound-waves. It may be arranged completely separate therefrom. For instance there may be erected stationary walls at certain places along a railway-line, the shape or the arrangement, or both, being so chosen, that the sound-waves are deflected to a direction in which they are not further disturbing the neighbourhood.

I claim:

1. The method of damping noises caused by propellers and other quickly moving parts, for instance quickly rotating parts, high-speed tram-cars, high-speed railway-cars and the like included, consisting in intercepting the respective sound-waves by sound-damping or sound-reflecting surfaces provided in suitable position at the places to be protected from being disturbed by those waves, substantially as set forth.
2. The method of damping noises caused by propellers and other quickly moving parts, for instance quickly rotating parts, high-speed tram-cars, high-speed railway-cars and the like included, consisting in intercepting the respective sound-waves by sound-damping or sound-reflecting walls arranged in suitable position at the places to be protected from being disturbed by those waves, substantially as set forth.
3. A device for damping noises caused by the propellers of propeller-driven high-speed railways, comprising in combination with the respective propeller, an annular member encompassing it, the sectional area of said member in the axial direction of the same being designed according to stream-lines, substantially as set forth.
4. A device for damping noises caused by the propellers of propeller-driven high-speed railways, comprising in combination with the respective propeller, an annular member encompassing it, a top rib and lateral fin-like parts, connecting said member with the body of the respective car, substantially as set forth.

In testimony whereof I affix my signature.

FRANZ KRUCKENBERG.
